UNITED STATES PATENT OFFICE.

STEWART H. HARTSHORN, OF SHORT HILLS, NEW JERSEY, ASSIGNOR TO STEWART HARTSHORN COMPANY, OF EAST NEWARK, NEW JERSEY, A CORPORATION OF NEW JERSEY.

SHADE ROLLER.

Application filed August 6, 1923. Serial No. 655,850.

To all whom it may concern:

Be it known that I, STEWART H. HARTSHORN, a citizen of the United States, and a resident of Short Hills, county of Essex, and State of New Jersey, have invented a certain new and useful Shade Roller, of which the following is a specification.

The invention relates to shade rollers and more particularly to spring shade rollers which are arranged vertically instead of horizontally as in window shade rollers, but it is to be understood that the invention is not limited to such use and may be carried out in connection with any type of drum or roller on which a flexible element may be wound and unwound.

The object of the invention is to produce a tubular roller of great strength and at a low cost.

A further object is to provide means, other than the material of the flexible element, for supporting the same on the roller.

A further object is to provide means whereby the flexible element will not be injured or destroyed by accidental removal from the roller.

These and further objects will more fully appear in the following specification and accompanying drawings considered together or separately.

One embodiment of the invention is illustrated in the accompanying drawings, in which like parts in all of the several figures are designated by corresponding characters of reference, and in which—

Fig. 1 is a side elevation, partly broken away, of a spring roller embodying the invention.

Fig. 2 is a fragmentary side elevation of a curtain or shade.

Fig. 3 is an end elevation of the roller.

Fig. 4 is a similar view viewed from the opposite end, and

Fig. 5 is a transverse section of a roller with the curtain or shade element in position.

In the embodiment of the invention illustrated in the drawings, the invention is shown as applied to a vertically arranged

roller, for use in bridging the bellows of 50 railroad car vestibules.

The roller 1 is illustrated as a sheet metal cylinder with a groove 2 extending longitudinally thereof, as is common with rollers of this type, and the tube 1 is reinforced, 55 not only by the member forming the groove, but by means of a sheet metal lining 3. The lining may be, and preferably is, of the same gauge as the metal of the tube 1, but may be made of heavier or lighter 60 stock if desired.

The lining 3 may be rolled or otherwise formed to approximately cylindrical form but of a diameter somewhat greater than the bore of the tube 1, but as the lining 65 is not a cylinder its longitudinal edges will be spaced apart forming a gap extending the length of the lining. The lining may be squeezed to reduce its more or less cylindrical diameter to somewhat less than 70 that of the bore of the tube 1; it may then be inserted in the tube, the grooved portion of the latter lying in the gap between the longitudinal edges of the reinforcing lining. The elasticity of the lining will 75 cause the same to tightly engage within the bore of the tube.

Secured in any suitable manner at one end of the tube 1 is a cap 4 having a central opening which forms a bearing for a 80 spear 5 of rectangular cross section. The cap 4 is provided with a notch 6 in line with the groove 2.

The opposite end of the tube 1 is enclosed by means of a cap 7. The cap 7 is not 85 notched as is the cap 4, but completely encloses its end of the tube. The cap 7 carries the usual pintle 8, and is provided with an annular rim 7a.

In connection with the roller 1 above described is employed a screen 9 of heavy cloth. One vertical edge of the screen is hemmed to form a pocket, in which is inserted a stout wire rod 10. The rod is of greater length than the screen and one end projects below 95 the bottom thereof.

The opposite vertical side edge of the screen is hemmed to form a pocket within

which is disposed a batten 11, and to the center of the batten is secured a loop 12 which cooperates with a hook or shackle (not shown) for securing the screen in extended position.

In operation the screen is made up with the rod 10, batten 11 and fixture 12 in position. The rod 10 may be secured against longitudinal movement in any desired manner.

The projecting end 13 of the rod is seated in the cup of the cap 7 in line with the groove 2 and with its lower end resting on the cap, thus retaining the screen against movement longitudinally of the roller. The rim 7^a will prevent lateral displacement of the end of the rod. That portion of the screen carrying the rod is now inserted in the groove, as shown in Fig. 5. The screen is now wound around the roller, as shown in Fig. 5 and is retained in such position by the engagement of the end of the rod with the cap 7 and by said winding.

The pindle 7 is inserted in a bracket carried on or near the platform of a car, and the spear 5 is inserted in a rectangular opening in a bracket on or near the roof of the same platform.

When two cars are coupled together the free edge of the screen carrying the batten 11 is pulled across the space between the adjacent platforms of the cars, and the loop 12 is secured to a shackle on the other platform.

The unwinding of the screen will wind the spring 14 of the roller 1 and the screen will remain taut notwithstanding any movements of the cars relatively to each other.

When the cars are uncoupled the loop 12 will be cast off the shackle, and the screen will be automatically wound upon the roller 1 by means of the spring 14. Should the attendant fail to cast off the loop 12, or should the cars become uncoupled accidentally during transit, the loop 12 will remain fast to the shackle, and as the cars part, the screen will be unwound from the roller and the rod 10 will be pulled from the slot 2 without destroying the screen.

The invention may be employed in connection with window shade rollers to prevent tearing the shade if pulled down too far, it being understood that when used as a window shade roller, the cap 4 will carry the usual pawls adapted to cooperate with a locking notch carried by the spear 5.

The lining 3 will reinforce the tube 1 and is unsecured thereto except by means of its own elasticity. The walls of the groove 2 lying in the gap between the edges of the lining, will prevent the lining from turning relatively to the tube 1.

In accordance with the provisions of the patent statutes the principle of the invention has been described, together with the

apparatus which is now considered to represent the best embodiment thereof, but it is desired to have it understood that the apparatus shown is merely illustrative, and that the invention may be carried out in other ways.

The invention having been described what is claimed as new and desired to be secured by Letters Patent of the United States is—

1. A device of the character described, comprising a vertically arranged cylindrical member, there being a longitudinal groove in the surface of the member, said groove being of less length than the member whereby a wall is formed at one end of the groove, and an element carried in the groove, said element engaging the wall whereby the element will be supported thereby, the width of the groove being greater than the lateral dimension of the element. 75

2. A device of the character described, comprising a vertically arranged cylindrical member, there being a longitudinal groove in the surface of the member, said groove being of less length than the member whereby a wall is formed at the lower end of the groove, and an element carried in and extending longitudinally of the groove, one end of said element engaging the wall whereby the element will be supported thereby, the width of the groove being greater than the diameter of the element. 90

3. A device of the character described, comprising a vertically arranged cylindrical member, there being a longitudinal groove in the surface of the member, said groove being of less length than the member whereby a wall is formed at the lower end of the groove, a rod carried in and extending longitudinally of the groove, said rod resting on the wall whereby the rod will be supported thereby, and a flexible sheet secured by one edge thereof to the rod, the width of the groove being greater than the diameter of the rod. 100

4. A device of the character described, comprising a vertically arranged cylindrical tubular member, there being a groove formed in the outer surface of the member and extending longitudinally thereof, the member being enclosed by a cap at the lower end thereof, said cap forming a wall at the lower end of the groove, a rod resting within the groove and extending longitudinally thereof, one end of said rod engaging said cap and being supported thereby, and a flexible sheet secured to the rod, the width of the groove being greater than the diameter of the rod. 105

5. A device of the character described, comprising a vertically arranged cylindrical tubular member, there being a groove formed in the outer surface of the member and extending longitudinally thereof, the member being enclosed by a cap at one end thereof, 115

said cap forming a wall at that end of the groove, a rod resting in the groove and extending longitudinally thereof, said rod being of less diameter than the width of the 5 groove, and a flexible sheet secured to the rod, said sheet having a pocket in which the rod lies, the ends of the rod projecting from

said pocket, said rod resting on the cap to support the rod, the rod being retained in the groove by winding the sheet around the 10 member.

This specification signed this 3rd day of August, 1923.

STEWART H. HARTSHORN.
